(57) **CLAIM**

We claim the ornamental design for a lighting device, as shown and described.

DESCRIPTION

FIG. 1 is a top perspective view of the design.

FIG. 2 is a bottom perspective view of the design.

FIG. 3 is a bottom view of the design.

FIG. 4 is a top view of the design.

FIG. 5 is a front view of the design.

FIG. 6 is a rear view of the design.

FIG. 7 is a left side view of the design.

FIG. 8 is a right side view of the design; and,

FIG. 9 is a top perspective view of the design with the light arm extended.

Any broken line(s) shown are for illustrative purposes only and form no part of the claimed design.
